FOOD DISPLAY WARMER

Robert G. Wilson, 643 E. Faris Road,
Greenville, S.C. 29605

Filed Sept. 7, 1965, Ser. No. 86,891

Term of patent 14 years

(Cl. D81—10)

FIG. 1.

FIG. 2.

FIGURE 1 is a perspective view of a food display warmer embodying my new design, and

FIGURE 2 is a rear perspective view thereof.

The dominant features of my design reside in the portions shown in full lines.

I claim:

The ornamental design for a food display warmer, substantially as shown and described.
